UNITED STATES PATENT OFFICE.

ALEXANDER MYERS, OF REVERE, MASSACHUSETTS, ASSIGNOR TO INTERNATIONAL COMFORT CHAIR CO., OF BOSTON, MASSACHUSETTS, A PARTNERSHIP CONSISTING OF ALEXANDER MYERS, LOUIS H. BURACK, SAMUEL HURWITZ, AND ALBERT HURWITZ, ALL OF BOSTON, MASSACHUSETTS.

CHAIR-AWNING.

1,155,366.

Specification of Letters Patent.

Patented Oct. 5, 1915.

Application filed October 29, 1914. Serial No. 869,303.

To all whom it may concern:

Be it known that I, ALEXANDER MYERS, a citizen of the United States, residing at Revere, in the county of Suffolk and State of Massachusetts, have invented a new and useful Chair-Awning, of which the following is a specification.

My invention relates to awnings used in combination with the ordinary types of so called comfort, steamer and lawn chairs, preferably the folding and collapsible types of same.

The object of my invention is to provide a frame, to which is secured a covering of canvas or other suitable material, which is provided with supporting members for engaging the same in proper position with the above mentioned types of chairs, principally for shielding the person seated in the same

from the hot rays of the sun.

Another object is to provide an awning for collapsible and folding chairs which may be permanently and foldably attached thereto, taking up but little additional room and designed to permit the same to be set in working position or otherwise, as desired.

Another object is to provide an awning for the above types of chairs, which may be attached to the same in a manner that permits it to be used either as a sun-shade or as a wind-shield, according as desired,—the latter being accomplished by simply disengaging the engaging end of the awning from the chair and swinging the awning forward to the front of the chair.

Still another object is to provide an awning, especially for out-door chairs, which may be adjusted and fixed to stay at any angle suitable to the person seated within the chair.

To these as well as other ends, my invention consists in the novel features of construction, combination and arrangement of parts set forth in the following specification, and particularly pointed out in the subjoined claims.

Referring to the accompanying two sheets of drawings,—Figure 1, is a perspective view of a common type of folding steamer or lawn chair, equipped with my awning, showing the same set in working position, with half of the canvas covering torn away for showing the frame of the same. Fig. 2,

is a perspective view of a similar type chair to that shown in Fig. 1, equipped with an awning, but shows the same set back in the non-working position. Fig. 3, is a view taken on line 3—3 in Fig. 1, looking in the direction of the arrows, showing the awning frame upon which is secured the canvas covering. Fig. 4, is an enlarged view of the engaging end of the awning-frame shown set on the pin provided in the top of the arm of the chair for the same. Fig. 5, is a front view of the top part of the chair, showing the arms of the same provided with the projecting-pins for engaging with the awning-frame, as shown in Fig. 1. Fig. 6, is a plan view of the awning-frame, showing the engaging end set in position on the projecting-pins provided in the arms of the chair for the same. Fig. 7, is a view showing a folding chair, equipped with my type of awning, folded,—the canvas of the awning being removed to show the relative position that the awning-frame takes with the chair when folded. Fig. 8, is a perspective view of the awning frame, set in an intermediate position with the chair for varying the angle of the awning, the second rung being shown resting against the upper ends of the arms of the chair. Fig. 9, is a front view of Fig. 8, but shows the awning frame supplied with the awning covering. Fig. 10, is the same view as Fig. 1, but shows a person seated in the chair with the awning lowered and used as a wind-shield instead of a sun-shade. Fig. 11, is a front view of Fig. 10 showing the awning lowered and used as a wind-shield.

In that embodiment of the invention shown in the drawings, the numeral 1 is an ordinary folding steamer chair, having the legs 2 pivotally engaged with the arms 3 by means of the pivot-studs 4. Secured to the end-rung 5 of the legs 2 and the top-rung 6 of the arms 3, is the canvas stretcher 7. The legs 2 are provided with the recesses 8 in which the rung 9 of the adjusting rods 10 fit for supporting the arms 3 to which the rods 10 are pivotally engaged at 11.

In Fig. 1, the top-rung 6 of the arms 3 is provided with extension pins 12 on the ends of the same, projecting beyond the arms 3 for engaging with the awning-frame.

The awning-frame is preferably made of

wood, with the sides 13 fixed apart by the rungs 14. The ends 15 of the sides 13 are provided with recesses 16 to fit over the pins 12, as shown in Fig. 1. Pivotaly fixed to the sides 13 are the frame supporting-arms 17, the lower ends 18 of which may be secured to the arms 3 in any suitable manner, preferably as shown in Fig. 1, where the same are pivotally secured to the pivot-studs 11. Stretched over the awning-frame is the cover 19 which is preferably made of canvas or other suitable material and provided with the side border 20. The cover 19 may be secured to the awning-frame in any suitable manner.

It may be noted here, that by making the pins 12 project sufficiently beyond the arms 3, the same will act as stops for the supporting-arms 17 to come up against when the awning is pushed back to the position shown in Fig. 2.

In Figs. 8, 9 and 10, 13^a are the sides of the awning-frame, having the brackets 21 secured to the engaging ends 15^a. The end-rung 14^a passes through the bracket 21 and the ends 15^a for forming the opening 22 into which is fitted the tops 23 of the arms 3. The side 24 of the bracket 21 is preferably provided with the recess 25 for fitting over the top-rung 6 of the arm 3 (Fig. 10).

Having thus described the parts of my invention in detail, the manner in which the same may be used is as follows:—Any ordinary folding chair of a similar type to that indicated in the drawing, especially in Fig. 1, may be easily equipped with my type of awning by simply providing the chair with the projecting-pins 12, which may be either extensions of the top-rung 6 or dowel-pins 40 of wood or metal fixed to the arms 3 for supporting the so-called engaging ends 15 of the awning-frame; and by either pivotally securing the lower ends 18 of the supporting-arms 17 with the pivot-studs 11, or by 45 pivotally securing said lower ends 18 with the arms 3 of the chair anywhere away from the pivot-stud 11,—thereby properly securing the awning-frame to the chair, to permit the same to fold along with the awning 50 in the same manner as it ordinarily would before the awning was attached thereto. Thus, it will be observed, that the awning-frame may be folded and closed up with the chair by simply disengaging the engaging ends 15 from the engaging projecting studs 12, and then shifting the awning-frame 55 to close up with the chair, as shown in Fig. 7.

It may be further observed that in securing the awning to the chair, as has just been described, and providing extension-studs 12 of an appreciable length, that by disengaging the engaging end 15 of the awning-frame, the awning may be set back into an intermediate position as shown in Figs. 8 60 and 9, or into a non-working position and

held in place by the projecting-pins 12 engaging with the supporting-arms 17, as shown in Fig. 2,—thus enabling the chair to be set in working position with the awning drawn back, when the same is not desired to protect the person, seated in the chair, from the rays of the sun. Also, it may be observed that the awning may be swung forward while the chair is set into working position for use as a wind-shield, 75 by simply disengaging the engaging end of the awning from the chair, as shown in Figs. 10 and 11. It may thus be understood that a chair supplied with an awning of the type herein described is specially useful at 80 beaches and sea shore resorts to bathers, for protecting them against sun burns when the rays of the sun are strong, and for affording them protection against strong winds in cool weather, by permitting the awning to assume a position which acts as a wind-shield instead of a sun-shade. It may also be understood that the chair, supplied with an awning as herein described, affords a very useful and convenient chair for infants and 85 children to sleep in out doors,—the awning being applicable to be used either as a sun-shade or as a wind-shield, according as the weather requires.

While I have shown the awning-frame 90 shaped rectangularly and have suggested the same built of wood, I do not wish to be limited against using any other shape of awning-frame, or against building the same from material other than wood. While 100 I have shown the covering of the awning preferably made of canvas, I do not wish to be limited against covering the frame with any other suitable material; such as wood, glass, et cetera. While I have shown 105 the awning provided with a short downwardly projecting border 20, I do not wish to be limited against lengthening the same to any desired length, even to reach the level upon which the chair rests when set 110 into working position. Also, while I have shown the awning-frame supplied with rungs for holding the sides of the same secured in position, I do not wish to be limited against employing any other method 115 of securing the sides, as desired.

While the preferred embodiments of my invention have been described in detail, it will be understood that I do not wish to be limited to the particular construction set 120 forth, since various changes in the form, material, proportion, arrangement of parts, and in the details of construction may be resorted to without departing from the spirit and scope of the invention, or destroying any of the advantages contained in the same, heretofore described and defined in the subjoined claims.

What is claimed is:—

1. A chair awning of the character de- 130

scribed, consisting of an oscillating covered frame member, adapted to be swung to the front or to the rear of the chair, and having an engaging end provided with disengaging means for disengagingly engaging said end with the back of the chair when the frame member is set in the sun-shade position; and oscillating supporting-arms having the upper ends of the same pivotally secured toward the opposite end of said frame member and the lower ends pivotally secured to the arms of the chair for swingingly engaging said frame member with said chair.

15 2. A chair awning of the character described, consisting of a rigid covered frame member having one end of the same provided with recesses for engaging with the chair to which the same is attached; swing-
20 ing supporting-arms having the upper ends pivotally secured to the frame member, near the end opposite the end provided with said recesses, and the lower ends adapted to pivotally engage with said chair for swing-
25 ingly engaging said awning with said chair, substantially as shown.

3. A chair awning of the character described, consisting of a rigid frame member having a projecting end, an engaging end, and intermediate engaging means for holding said frame member in set position

with the top of the chair; swinging supporting-arms having the upper ends pivotally secured to the sides of said frame member and positioned near to the projecting 25 end of the same, and the lower ends adapted to be pivotally secured to said chair for swingingly engaging said awning with said chair; and a cover member adapted to inclose and cover said frame member substantially as shown.

4. A chair awning of the character described, consisting of a rigid frame member provided with a projecting end and an engaging end adapted to be detachably secured to the top of a chair; swinging supporting-arms having the upper ends of the same pivotally secured to the sides and near to said projecting end of the same, and the lower ends of said supporting-arms adapted 50 to be pivotally secured to the chair for permitting said frame member, when the engaging end of the same is disengaged from the upper end of the chair to swing forward or backward on same or to fold and close 55 with said chair; and a covering member adapted to fit over said frame and inclose the same, substantially as shown.

ALEXANDER MYERS.
